RAILROAD TRACK

Watkin F. Jones, Upper Darby, Pa.

Application March 2, 1938, Serial No. 193,426

3 Claims. (CL. 238—10)

My invention relates to a new and useful railroad track and it relates more particularly to a track adapted for use in connection with the various kinds of toy mechanical and electric trains.

My invention further relates to a railroad track of this character which both functionally and in appearance is identical with standard commercial railroads thus giving the electric train a realistic appearance which is a feature of great value in its psychological implication on the persons amusing themselves with such a train.

My invention still further relates to a railroad track which is extremely inexpensive to produce, extremely easy to assemble, which can be formed in straight and curved sections as desired, and which, while affording a firm foundation, also affords sufficient flexibility thus insuring against derailment, which, as all who have had experience in running electric toy trains know, is a great disadvantage and sometimes is serious enough to detract greatly from the amusement value of the apparatus.

Another object of my invention is to so construct my novel track as to provide extensive rubber and air cushioning between the track and the floor of the room in which the train is to be operated thus greatly minimizing the sound and vibration attendant upon the operation of such trains which ordinarily are a cause of great annoyance to people not participating in the train operation.

My invention still further relates to a railroad track the curved sections of which are adequately banked, thereby, not only simulating actual railroad construction, but also insuring against derailment while the train is going over a curve.

My invention still further relates to a novel effective and extremely simple means of joining adjacent track sections together in a manner which precludes longitudinal displacement, the rail assembly being firmly and yet resiliently engaged by the track thus precluding lateral displacement.

My invention still further relates to a railroad track the manufacture of which lends itself to easy adaptation or variation in order to accommodate various types of toy electric trains such as are now or may later be on the market.

In the accompanying drawing;

Fig. 1 represents a top plan view of a portion of a railroad track embodying my invention.

Fig. 2 represents a section on line 2—2 of Fig. 1.

Fig. 3 represents a view similar to Fig. 2 showing the manner in which the rails are applied to the track.

Fig. 4 represents a section on line 4—4 of Fig. 1.

Fig. 5 represents a section on line 5—5 of Fig. 1.

Fig. 6 represents a section on line 6—6 of Fig. 1.

Fig. 7 represents a section on line 7—7 of Fig. 1.

Fig. 8 represents a view similar to Fig. 6 showing the manner in which the track engages a piece of rail section which is mounted on a metal base.

Referring to the drawing in which like reference characters indicate like parts, and more particularly to Fig. 2, 10 designates the base of the track which is in the nature of a mat formed of rubber or other resilient, sound-deadening material and of sufficient thickness to constitute a support and afford effective cushioning. The base 10 is provided with the spaced lugs 12 which are preferably of the same material as the base 10 and which may be suitably secured thereto or preferably molded integral therewith. The lugs 12, when viewed in top plan as in Fig. 1, extend from the inner and outer edges 14 and 16 towards the center of the base 10 thus accurately simulating the appearance of the wooden ties to which the ordinary rails of commercial railroads are usually secured by spikes or the like. The lugs 12 are provided with overhanging edges 18 which engage corresponding flanges 20 of the inner and outer rails 22 and 24. The rails 22 and 24 are interconnected to each other and to the center or third rail 26 by the metal pieces 28. The rails 22, 24 and 26 and the cross piece 28 are the conventional type now on the market and are sold in sections varying in length from a few inches to a foot or more, and, when a purchaser buys an electric train, he buys as many sections, straight or curved, as he desires for making a track for the train. Heretofore, and in the absence of a track such as I have invented or as may have been attempted, the practice was to build a platform or to lay the rail sections when assembled on the floor of the room either on the wood or on the rug. In either case the rail sections thus assembled did not present a steady support thus resulting in frequent and annoying derailment, and furthermore, when the rails were laid on a wooden floor, the rumbling of a train running over the floor caused an extremely annoying disturbance. If, in order to steady the rails to avoid derailment, they were nailed to the floor, it resulted in excessive damage, and to avoid this it has been customary to build a platform especially

for the rails long before Christmas or any occasion on which it is desired to use the train. The building of such a platform was expensive and troublesome, and, while it was being built and 5 during its use, it occupied space which was otherwise needed and furthermore it greatly detracted from the element of surprise since the children knew that they would get the electric train when they noticed the preparation of the platform long 10 before Christmas or other festive occasion. With my novel track I am enabled to assemble a train instantaneously and in any desired location on the floor or on a rug and without the necessity of any special platform.

15 By making the base 10 of the proper width, and by properly spacing the overhanging edges 18, I adapt my novel track to the standard ordinary rail sections as they are available on the market, and, in order to apply the rail sections 20 to my track, it is merely necessary to grasp the opposite lugs 12 and deflect them and the base substantially as shown in Fig. 3 and then drop the rail section on the base 10 so that, when the tension is relieved, the track rebounds into position as shown in Fig. 2 in which the overhanging edges 18 engage the flanges 20 of the adjacent rails 22 and 24. This completely obviates the necessity of nailing, tacking or otherwise fastening the rails to the platform and affords 30 sufficient tension and engagement to retain the rails in position firmly but resiliently but it will be noted, particularly as seen from Fig. 7, that neither the rails nor their connecting pieces 28 rest on the base 10 proper, but that they are suspended and spaced therefrom. On the contrary, the rails themselves rest upon the bridge 30 which extends completely across the base between the lugs 12. This produces a method of support at spaced points whereby the major part 40 of the vibration takes place on the suspended portions of the rails and whereby, where the rails do rest on the bridge 30, as at 32 in Fig. 7, there is a double thickness of rubber under them thus reducing the noise and vibration more than 45 it would be reduced if the rails 20, 24 and 26 and their cross pieces 28 rested directly on the base 10.

In Fig. 1 I have shown a curved section A and a straight section B, and, as will be seen from Fig. 2, the bridge 30 is thicker at the point supporting the rail 24 than it is at the point supporting the rail 22, whereas, in Fig. 6 it will be seen that the bridge 30 is of a uniform thickness throughout. Since Fig. 2 is along the line 2-2 of Fig. 1 and is a cross section of the curved portion A it will be seen that with the increased thickness under the rail 24, and with the thickness decreasing towards the point under the rail 22, the curved section A is banked or inwardly 55 sloped in the manner in which commercial road tracks or motor highways are sloped along the curves to insure against derailment and facilitate turning. Fig. 6, which is on the line 6-6 of Fig. 1, is a cross section through the track B which is straight and needs no banking and therefore the bridge 30 is of uniform thickness along its entire extent. At the junctions of the sections A and B I preferably reduce the width 60 of the lugs 12 somewhat as at C and D and I utilize the U-shaped clamp 34 which engages the reduced lugs C and D and holds them together, it being understood that the rails on the sections A and B are provided with prongs and sockets 65 which are the conventional means for connecting the rails together.

The manufacturers of rails for toy trains supply switch sections by means of which the train can be made to cross from one set of rails to another, and such switch sections, comprising the proper combination of rails 22, 24 and 26, are 70 usually mounted as a unit on a switch.

In Fig. 8 I have illustrated the manner in which a switch section mounted on a metal base 36 can be laid upon and engaged by my novel track in which it will be seen that the overhanging edges 18 of the lugs 12, instead of engaging the flanges 20 of the inner and outer rails 22 and 24, engage the edges 38 of the supporting plate 36 directly.

It will thus be seen that my novel track, formed 15 in sections of suitable length and proper width, can be sold either as a part of toy train sets, or can be sold separately for use in connection with the millions of feet of track of rails now in use, and that my track, not only completely simulates 20 the commercial railroad track construction thus making greater appeal by its more realistic appearance, but that it also affords a firm and resilient base which can be instantaneously laid out or removed and which can be instantaneously 25 engaged or disengaged from the rails. My novel track also affords a maximum degree of cushioning and sound-deadening by the suspension of the rails and their cross pieces between the 30 bridges 30 and by supporting the rails on the combined thickness of the base 10 and bridge 30. Furthermore, the engagement of the rails themselves 35 directly by the overhanging edges 18 instead of engaging the cross pieces 28 applies the support and resiliency directly to the rails thus insuring against slippage and at the same time permitting the rails to "give" in the manner 40 prevailing in commercial railroad tracks which have been found to be the best means for permitting fast travel of long and heavy trains without danger of derailment. Also, the banking of the curved sections A by the tapering of the supporting bridges 30 further insures against derailment.

While it is conceivable that the sections A and 45 B can be manufactured in other ways, I find it preferable to mold such sections so that the base 10, the bridges 30, the lugs 12 representing the cross-ties and their overhanging edges 18 engaging 50 the flanges 20 of the rails, are made in one piece.

Having thus described my invention, what I 55 claim as new and desire to secure by Letters Patent is:

1. A base for a conventional toy train track section formed of rigidly interconnected rails, comprising, a continuous resilient base, transverse resilient bridge members integral with and raised above the upper face of said base adapted 60 to support said track section out of contact with said base by direct contact of said bridge members with said rails, and lugs on the ends of said bridge members having inwardly overhanging portions adapted to engage the outer bottom flanges of said rails.

2. A base for a conventional toy train track section formed of rigidly interconnected rails, comprising, a continuous resilient base, transverse resilient bridge members fixedly positioned 70 upon and raised above the upper face of said base and adapted to support said track section out of contact with said base by direct contact of said bridge members with said rails, and lugs on the ends of said bridge members having in- 75

wardly overhanging portions adapted to engage the outer bottom flanges of said rails.

3. A base for a conventional toy train track section formed of rigidly interconnected rails, comprising, a continuous resilient base, transverse resilient bridge members fixedly positioned upon and raised above the upper face of said base adapted to support said track section by direct contact of said bridge members with said

rails and thickened portions on the ends of said bridge members constituting abutments for the webs of the outer rails of said track section, there being horizontal recesses formed in said thickened portions at their junctions with said bridge members for receiving and clamping the outer bottom flanges of said rails. 5
